OIL BURNER CONSTRUCTION

Norman Franklin Bennett, Newmarket, Ontario,
Canada

Application February 18, 1935, Serial No. 7,096

9 Claims. (Cl. 299—140)

The principal objects of this invention are to provide a device which will thoroughly atomize oil used for fuel purposes including very heavy oil and effect the mixture of same with air so that the resultant mixture will ignite instantaneously with spark ignition under varying conditions of atmosphere and temperature and will maintain a constant and uniform flame, thereby enabling the use of the device in intermittent service such as is required for house-heating equipment.

The principal features of the invention consist in the novel construction and arrangement of mechanisms whereby the oil is fed to a rotatable member from which it is discharged into a constricted chamber into which air is directed under pressure by a converging annular wall, and the oil is broken into extremely fine particles and mixed with inflowing air by an agitator member extending axially from the rotatable member into the constricted chamber.

A further important feature of the invention consists in conducting the oil to the rotatable member through a channel surrounding the rotatable member and applying heat thereto to preheat the oil prior to its being discharged into the mixing chamber.

Referring to the drawings:

Figure 1 is a side elevation partly in section of my oil burning apparatus.

Figure 2 is a plan view also partially in section and with the top cover plate removed from the casing.

Figure 3 is an enlarged sectional elevation of the oil feeding unit showing the central shaft, the nozzle construction, the preheater and the oil pipe leading to the oil feeding unit from the pump.

Figure 4 is a sectional view of the outer stationary nozzle showing the air pipe connecting therewith.

Figure 5 is an end elevation of the outer stationary nozzle.

Figure 6 is a sectional view of the inner rotary nozzle illustrating the multi-faced agitating blade.

Figure 7 is an end elevation of the inner rotary nozzle.

Figure 8 is an enlarged longitudinal sectional view of the assembled nozzle.

Figure 9 is an enlarged longitudinal part sectional elevational view of the nozzle structure taken at right angles to the plane of the section illustrated in Figure 8.

Referring more particularly to the drawings, A indicates the device as a whole, which includes the oil feeding unit 10 which is generally surrounded by the casing 11 supported from the framework of other parts of the apparatus. This includes the driving motor 12, the fan 13, air compressor 14 and oil pump 15. The arrangement of

various elements could, of course, be modified should this be desired but the disclosure made particularly in Figures 1 and 2 illustrates a very compact and efficient unit.

One of the salient features of my invention 5 resides in the construction and arrangement of the oil feeding unit including the attached nozzle construction, the oil feeding unit being in the form of a tubular member which is preferably connected at one end of the pump casing 15 and 10 carries on its opposite end a stationary nozzle 16. Within the oil feeding unit 10 is a shaft 17 which is placed in driving connection with the shaft 18 the latter being driven by the motor, and operating the fan, compressor and pump, so that shaft 15 17 is constantly rotated during the operation of the motor. The relation between the oil feeding unit 10 and the shaft 17 is such that between them, there is provided a space or clear passage-way 19 for supplying the oil to the nozzle, the 20 construction preferably being such that the shaft is reduced in diameter intermediately of its length so as to provide the space 19, the larger ends of the shafts 20 and 21 forming bearings.

Through the outer end of the shaft 17 extending up to and through the enlarged portion 21 is a bore 22 which is intersected by the transverse passage or passages 23 that communicate with the space 19 so that oil may be fed through this latter space, through the transverse passages 23 30 into the bore 22, from whence it is ejected to be discharged from the nozzle 16.

The reduced portion of the shaft 17 is preferably formed with screw threading or the like 23 so that as the shaft constantly rotates during 35 the operation of the apparatus, the oil, regardless of the fact that it may be very sluggish due to cold weather, will always be positively passed through the channel or space 19 surrounding this shaft and, while the pressure set up by the pump 40 usually would be sufficient to provide for the ejection of the oil from the burner nozzle, it is apparent that when the oil is sluggish and will not so readily respond to the pressure of the pump this rotating shaft formed with screw 45 threading or the like will constitute a positive agitator and provide for a steady ejection of oil.

The rotating shaft also serves a very important function in providing for the breaking up of the oil into a finely atomized spray, which is taken 50 care of by various expedients. In this connection the end of the shaft is provided with a nipple 24 or other suitable means for receiving a rotary nozzle 25 which is rigidly secured on the end of the shaft in driving engagement therewith so 55 that when the shaft rotates the nozzle does likewise. The nozzle 25 is formed with a chamber 26 which communicates with the bore 22 of the shaft, the other end of the nozzle being formed preferably with a pair of discharge openings 27 60

between which, and projecting from the end of the nozzle, is an agitating member in the form of a blade 28 presenting a plurality of longitudinal faces which engage the streams of oil projected from the openings 27, thus breaking up the streams and throwing the oil outwardly against the wall of the nozzle 16. This blade is disposed between the orifices 27 which are positioned above and below opposite faces of the agitator.

10 As shown, the rotary nozzle 25 is spaced from the stationary nozzle 16, the blade or agitator 28 projecting from nozzle 25 into the space between said nozzles. The stationary nozzle 16 is provided with a discharge opening 29 which is designed to register with the discharge openings 27 in nozzle 25 and the blade or agitator 28 is preferably tapered to a point or substantially so, as clearly illustrated in Figure 6 and Figures 8 and 9, so that it may project partially into the discharge opening 29 of the agitator and thus provide for a violent agitation of the oil as it passes between the discharge openings 27 of the rotary nozzle 25 and discharge opening 29 of stationary nozzle 16.

15 The nozzle 16 is tapered and particularly its inner surface, as at 30, the inner or rotary nozzle 25 having a portion tapered as at 31, or in other words its end is frusto-conical so that the space between the nozzles finally takes the form of a conical passageway converging at a point adjacent to the discharge opening 29 of the nozzle and the agitator 28. As shown in Figure 4 and Figures 8 and 9, the stationary nozzle 16 is provided with an opening 32 to receive the conduit 33 which is designed to supply compressed air to the space 20 between the nozzles so that in combination with the violent agitation of the oil by the agitating blade 28, a blast of compressed air converges on the blade and discharge opening 29 whereby the oil will be broken up into an extremely fine spray.

25 20 The stationary nozzle 16 is provided with a slot 34 intersecting the discharge opening 29 (see particularly Figures 4, 5, 8, and 9) so that the spray of atomized oil and air being discharged from the stationary nozzle may spread within the fire box.

30 25 Prior to passing to the rotary nozzle 25, the oil is partially broken up through the type of construction employed. For instance, as the oil passes from the passageway 19 in the oil feeding unit to the bore 22 of the shaft 17, it enters the passageways 23 which constantly rotate with the shaft and therefore the oil entering these passageways will be agitated and broken up and particularly so in view of the fact that the oil enters these passageways against the action of centrifugal force.

35 30 Moreover, when the oil is free flowing and under considerable pressure, it will be forced against the threading on shaft 17 which will tend to cause a breaking up of the fluid. In view of these facts, therefore, the oil, when it is discharged with the compressed air at the end of the nozzle, is broken up to such an extent that it will immediately ignite by means of a spark ignition. This is an extremely important point in view of the fact that great difficulties have been experienced in 40 providing for an instantaneous ignition of an oil spray by spark ignition and when it is considered that this can be effected regardless of the type of fuel oil used, the full importance of the development will be realized. Moreover, the ignition device can be positioned directly in advance and in the path of the spray, as will be referred to hereinafter.

45 An important feature in the construction of the oil feeding unit is the arrangement by which the oil may be instantaneously preheated while

being supplied to the nozzle and agitated, which is a factor in instantaneous ignition. For instance, by flowing the oil through the passageway 19 surrounding the shaft, a comparatively large volume of oil passes through the oil feeding unit, 5 but by reason of the fact that the passageway 19 is restricted in depth as between the interior wall of the oil feeding unit and the exterior surface of the shaft, a body of oil having a large surface area and limited depth flows through the oil feeding unit and therefore, by completely surrounding the surface of the oil feeding unit with an electric preheater 35 directly overlying the oil channel, the oil passing through this channel can be instantaneously heated. In other 10 words a thin body of oil is directly heated without sacrificing volume, the oil feeding unit shell being 15 preferably of brass or like metal which heats rapidly.

20 The preheater shown is provided with clamps or the like 36 to which the circuit wires may be attached and a movable clamp 37 is provided which may be moved along the preheater so that the amount of resistance wire through which the current passes can be changed to vary the amount 25 of heat desired. The preheater is operated on the general circuit employed for the driving motor, the circuit being of well known character including thermostat control and a relay and switch for general automatic control. In the 30 present case the connections are such that the preheater is cut in to operate just prior to the operation of the motor and the motor is automatically put into operation a few seconds later.

25 35 The casing 11 surrounding the oil feeding unit may be formed with a spider or other suitable support 39 through which the nozzle 16 may project. The spider or other device employed acts as a general support and may serve as a suitable mounting for the insulating bushings 40 of the 40 ignition electrodes 41. These latter are curved at their outer ends and spaced apart to provide a suitable spark gap and are positioned well in advance of the nozzle 16 and directly in the path of the atomized oil being discharged from the 45 nozzle so that under the conditions brought about by the apparatus, the spark ignition will bring about instantaneous combustion.

30 45 The inner ends of the ignition electrodes are provided with suitable clamping connections such as 42 to receive the circuit wires which are also connected in the general circuit for operating the motor and arranged in usual manner so that ignition takes place immediately that the motor starts and after combustion is established the ignition 50 circuit is cut out. The general circuit employed for this is of well known character.

40 50 The casing 11 may be provided with a removable cover plate 43 and is provided with an opening 44 regulated by a suitable slide damper or the like 60 45, the opening 44 being designed for connection with the conduit 46 of the fan 13 so that air for supporting proper combustion may be delivered through the gun casing into the fire box.

55 65 It will be noted that the motor, fan and compressor are all driven from a single shaft, the compressor being simply secured to the fan casing by means of a suitable mounting ring or the like 47 so that a very compact unit is provided 70 with provision for the driving of the shaft 17 in a very simple manner. The compressor is of ordinary form and through the compressed air supply line 33 which extends between the compressor and the nozzle 16, compressed air is con- 75

stantly supplied to the nozzle construction during operation of the apparatus.

The shaft 18, that is, the driving shaft from the motor, fan and compressor, also operates the oil pump 14 which is mounted directly on the casing of the compressor, the shaft 18 being provided with a worm 48 which meshes with worm wheel 49 on the pump shaft 50. The pump may be an ordinary gear pump driven from the shaft 50 and supplying oil through the valve 51 to the oil conduit 52, the valve being of any suitable type such as one in the nature of a sleeve having an opening through which the oil may discharge, the sleeve being rotatable to control the size of, 15 or to shut off the opening.

A particular feature which is notable is the very short oil delivery line 52 which eliminates possibility of clogging, as is often the case where it is necessary to employ long oil supply lines. 20 The oil is supplied to the pump from an auxiliary oil tank 53 which receives its supply from the main tank.

It is apparent therefore, that when the apparatus is in operation oil will be supplied at a constant desired pressure to the oil feeding unit, the oil being instantaneously preheated, then broken up finely through violent agitation resulting from the operation of the auxiliary agitating means, the multifaced agitating member 28 and the converging blast of air from all sides which is directed by the shape of the inner and outer nozzles. It is thus discharged in a fine atomized spray from the end of nozzle 16, whereupon ignition takes place and a very hot flame is produced.

35 In practice this burner has proved efficient when using various grades and types of oil as fuel, as well as used motor oil and due to the arrangement and construction of the parts described, it has performed efficiently with instantaneous ignition after a few seconds preliminary preheating, this favourable performance being due to the facility with which the oil may be heated, the manner in which even sluggish oil is positively fed, and the arrangement for constantly breaking up the oil into a very fine atomized condition. The preferred construction has, of course, been shown, but this may be modified to some extent while maintaining the principles employed.

50 What I claim as my invention is:—

1. An oil burner comprising a stationary nozzle converging to a discharge opening, a rotary nozzle arranged coaxial with said stationary nozzle and discharging oil longitudinally in the direction of the discharge of the stationary nozzle, a paddle-like agitating member extending longitudinally from the end of said rotary nozzle into the convergent discharge end of the stationary nozzle and rotating with said rotary nozzle to engage and break up the oil being discharged from said rotary nozzle, means for feeding oil to said rotary nozzle, and means for directing a blast of air through said stationary nozzle around said rotary nozzle.

65 2. An oil burner comprising a stationary nozzle converging to a cylindrical orifice, a rotary nozzle arranged co-axial with said stationary nozzle having openings in the end thereof discharging streams of oil in a longitudinal direction into said cylindrical orifice, an agitating member projecting from the end of said rotary nozzle and arranged between the oil discharge openings and having a plurality of longitudinal faces adapted to engage and break up the streams of oil, said agitating member extending into the cylindrical 70 discharge orifice of the stationary nozzle and

having its longitudinal edges rotating in close proximity to the cylindrical wall, means for feeding oil into said rotary nozzle, and means for directing a blast of air through said stationary nozzle around said rotary nozzle.

3. An oil burner as claimed in claim 2 in which the agitating member is in the form of a flat blade arranged co-axially of said rotating nozzle and between the oil discharge openings, the flat faces of said blade in rotation beating the lagging oil streams and throwing the oil against the surrounding wall of the stationary nozzle to be mixed with the flow of air through said stationary nozzle.

4. An oil burner as claimed in claim 1 in which the rotary nozzle is provided with a hollow chamber adjacent to the end and communicating with the discharge openings, said discharge openings being substantially parallel with the axis of said nozzle.

20 5. An oil burner comprising a stationary tubular member, a nozzle mounted on the end of said tubular member converging to a cylindrical discharge opening, a shaft rotatably mounted axially within said tubular member and spaced 25 from the inner wall thereof, said shaft having a central bore and passages connecting said bore with the annular space between the shaft and tube, a nozzle secured to the end of said shaft having a chamber therein, communicating with 30 said bore and having openings through the outward end thereof adapted to project thin streams of oil into the cylindrical discharge opening of the stationary nozzle, a blade extending from the end of said nozzle mounted on said shaft 35 and projecting into the discharge opening of the stationary nozzle to break up the oil flowing through said openings arranged either side of said blade, means for feeding oil through said tubular member and into and through said rotary 40 nozzle, and means for feeding a blast of air through said stationary nozzle around the discharge end of the rotary nozzle.

6. An oil burner as claimed in claim 5 in which the shaft is supported in a bearing closing the 45 outer end of the tubular member which separates the annular oil passage within the tubular member from the annular air chamber within the nozzle mounted on the end thereof.

7. An oil burner as claimed in claim 5 in which the portion of the shaft spaced from the enclosing tube is threaded externally to assist the delivery of an annular body of oil to the nozzle.

50 8. An oil burner as claimed in claim 5 in which the tubular member is threaded externally at its 55 end and the stationary nozzle is internally threaded and adjustably mounted on the threaded end of the tube to permit an adjustment of the spacing between the discharge end of the rotary nozzle and the inner wall of the discharge end 60 of the stationary nozzle to regulate the flow of air.

9. An oil burner as claimed in claim 1 in which the converging, stationary nozzle is of frusto-conical form and the discharge opening is an axially arranged cylindrical passage, and the rotary nozzle is of frusto-conical form having its tapering exterior wall substantially parallel with the tapering interior wall of the stationary nozzle, and having the discharge openings in the small end thereof arranged either side of the 70 axis of the burner and projecting streams of oil either side of the agitating member and into the cylindrical discharge opening of the stationary nozzle.
